(57) **CLAIM**

The ornamental design of a tablet computer enclosure with handles, as shown and described.

DESCRIPTION

FIG. 1 is a front perspective view of a tablet computer enclosure with handles.

FIG. 2 is a rear perspective view of the tablet computer enclosure with handles.

FIG. 3 is a front elevation view the tablet computer enclosure with handles.

FIG. 4 is a rear elevation view the tablet computer enclosure with handles.

FIG. 5 is a right side view of the tablet computer enclosure with handles. A left side view of the tablet computer enclosure with handles is a mirror image of FIG. 5; and, FIG. 6 is a top view of the tablet computer enclosure with handles. A bottom view of the tablet computer enclosure with handles is a mirror image of FIG. 6.

In FIGS. 1 and 3 of the drawings, the broken lines represent unclaimed portions of the claimed design and form no part of the claimed design.

1 Claim, 3 Drawing Sheets
